(57) **CLAIM**

The ornamental design for a punch retainer, as shown and
described.

DESCRIPTION

FIG. 1 is a perspective view of the design for a punch retainer
according to the present invention;

FIG. 2 is another perspective view of the punch retainer
shown in FIG. 1;

FIG. 3 is a top plan view of the punch retainer shown in FIG.
1;

FIG. 4 is a bottom plan view of the punch retainer shown in
FIG. 1;

FIG. 5 is a cross-sectional view taken along line 5—5 of FIG.
3; and,

FIG. 6 is a cross-sectional view taken along line 6—6 of FIG.
3.

The broken lines showing the beveled edges, vent passage,
threads, and other features are for illustrative purposes only
and form no part of the claimed design.
